UNITED STATES PATENT OFFICE.

THOMAS DANQUARD, OF NEW YORK, N. Y., ASSIGNOR TO THE AUTOPIANO CO., OF NEW YORK, N. Y., A CORPORATION OF NEW YORK.

TUBE-JOINT FOR METAL TRACKER-BARS AND METHOD OF FORMING THE SAME.

No. 880,508.

Specification of Letters Patent.

Patented March 3, 1908.

Application filed July 2, 1906. Serial No. 324,406.

To all whom it may concern:

Be it known that I, THOMAS DANQUARD, a citizen of the United States, residing at New York, in the county of New York and State of New York, have invented a new and useful Tube-Joint for Metal Tracker-Bars and Methods of Forming the Same, of which the following is a specification.

In certain modern and improved automatic musical instruments, it is desirable to use a tracker-bar of metal with lead or other soft metal tubes to convey the wind from the tracker-bar to the action mechanism, rubber tubing being impracticable in many climates. A difficulty has arisen as to the manner of connecting the lead tubes with the little brass tubes at the lower side of the tracker-bar.

The principal object of the present invention is to provide for accomplishing this result in such a manner that a tight and durable joint may be obtained without any heating or soldering which would be objectionable in this kind of instruments. This I accomplish by expanding the end of the brass tube, slipping the lead tube over the expanded portion, inserting cement and crimping the lead at a point between the expanded part of the brass tube and the end of the lead tube.

For a further description of a particular way in which the invention can conveniently be carried out, reference is to be had to the accompanying drawings in which,

Figure 1 is a transverse sectional view of the tracker-bar showing the outside of one of the joints. Fig. 2 is a plan of the same. Fig. 3 is a side elevation on an enlarged scale partly in section, showing the joint in the process of construction, and Fig. 4 is a similar view showing the completed joint.

It would be a simple matter to crimp the lead tube about the brass tube but a joint formed in this manner would not be tight and there would be no means for preventing slipping. For the purpose of insuring an absolutely tight joint and preventing any slipping of the parts, each brass tube a , which extends from the tracker-bar, is expanded at the end to form a bell a' . This expansion is made sufficiently great to enable the bell to be inserted in the end of the lead tube b and to make as tight a fit therein as may be convenient, and it has points a'' . It will be noticed that by forming this bell a shoulder a^2

is provided. A certain portion of the tube a , adjacent to the shoulder a^2 is covered with any suitable kind of adhesive, such as cement or other material calculated to make a tight joint or to assist in holding the two tubes together. The lead tube is then placed on the bell and extended to the end of the layer of cement, or if desired, the tubes can be placed in this position in the first place and the cement then applied, although this is not as convenient an operation as the one described above. When this is accomplished, the parts appear as is shown in Fig. 2.

The next step in the process consists in crimping the lead tube down onto the brass tube at the part on which the cement is applied; that is, between the shoulder a^2 and the end of the lead tube. This crimping may be done in any desired way and is conveniently accomplished by the use of an especially constructed tool somewhat in the nature of a pair of pliers.

It is to be observed that the crimping results in forming a pair of shoulders b' and b^2 , the latter being opposite the shoulder a^2 and both of these shoulders serving to hold these parts together and prevent their being displaced by any ordinary usage.

The cement, it must be remembered, is at this time in place between the cubes and as the crimping operation is preferably employed while the cement is in a plastic state, the latter can harden after the crimping operation is performed and thus add to the efficiency of the joint. However, a very tight joint can be secured without the use of cement, although such a joint would not be sufficiently tight for some purposes.

It will be seen, of course, that by the provision of the shoulders a^2 and b^2 , each tube is provided with means to prevent its being withdrawn from the other tube; hence, a double locking is secured and the parts are necessarily securely fixed together.

When the harder metal tube is on the inside, as described, it serves as a support for the soft metal tube during the crimping operation, whereby that can be performed without danger of crushing the inner tube, but the process can be carried out with tubes of the same hardness or even with the softer tube inside. The latter, however, requires special provisions to maintain the cylindrical shape of the inner tube, during the crimping operation.

While I have illustrated and described a particular form of joint which I at present prefer to employ and have set forth a preferred method of forming this joint, I am aware that many modifications may be made by any person skilled in the art and therefore, I do not wish to be limited to the exact construction or sequence of steps described and illustrated, but

10 What I do claim and desire to secure by Letters-Patent is:—

15 1. The combination of a relatively hard metal tube having an expanded bell-shaped end provided with a shoulder with a relatively soft metal tube of sufficient size to pass over the bell-shaped expanded portion of the first mentioned tube, said soft metal tube being crimped onto the first mentioned tube at a point adjacent to the shoulder thereof and 20 between said shoulder and the end of the outer tube so as to constitute a shoulder on the soft metal tube opposing the shoulder on the other tube and constituting the outside of said joint, said inner tube constituting a solid 25 backing for the outer tube when the latter is crimped thereon.

30 2. The combination of a tube having an expanded bell-shaped portion near one end thereof, a second tube fitting over the expanded portion of the first tube and extending beyond the inner end of said expanded portion, a layer of adhesive material located in a space between the two tubes, the outside tube being provided with a crimped portion

whereby it is forced into engagement with the outer surface of the inner tube at a point near the expanded portion thereof.

3. A method of joining a hard metal tube with a soft metal tube which consists in expanding the end of the inner hard metal tube 40 to substantially the diameter of the inside of the soft metal tube, passing the outer tube over the expanded portion of the inner tube to project a distance beyond the same, and applying force to crimp the outer tube on the 45 inner tube between the end of the outer tube and the expanded portion of the inner tube to form an inwardly projecting shoulder adjacent to the shoulder formed by the expanded end of the inner tube. 50

4. A method of uniting tubes which consists in expanding the end of the inner tube to provide a shoulder, passing the outer tube over the shoulder of the inner tube, placing an adhesive in the space between the two 55 tubes adjacent to said shoulder, and crimping the outer tube so as to form a shoulder therein opposite the shoulder on the inner tube to provide positive means for preventing each tube from being withdrawn from the 60 other.

In testimony whereof I have hereunto set my hand, in the presence of two subscribing witnesses.
